US00D767339S

(12) **United States Design Patent** (10) Patent No.: **US D767,339 S**
(45) Date of Patent: **** Sep. 27, 2016**

(54) **BOTTLE WITH STRAINER**

(71) Applicant: **FC Brands Limited**, Central Hong Kong (HK)

(72) Inventors: **David Dennys Chitayat**, Shanghai (CN); **Heather Tomasetti Kauffman**, Brooklyn, NY (US); **Pieter Schouten**, Berkeley, CA (US)

(73) Assignee: **FC BRANDS LIMITED**, Central Hong Kong (HK)

(**) Term: **14 Years**

(21) Appl. No.: **29/518,915**

(22) Filed: **Feb. 27, 2015**

(51) LOC (10) Cl. **07-01**

(52) U.S. Cl.

USPC **D7/523; D7/513; D7/399**

(57) **CLAIM**

The ornamental design for a bottle with strainer, as shown and described.

DESCRIPTION

FIG. 1 is a perspective view of a bottle with strainer according to our new design;

FIG. 2 is a front elevation view thereof, the left, right, and

rear elevation views being the same; and,

FIG. 3 is a bottom plan view thereof.

The broken lines shown represent unclaimed subject matter and form no part of the claimed design.

1 Claim, 3 Drawing Sheets
